UNITED STATES PATENT OFFICE.

CHARLES E. SACKETT, OF DANBURY, CONNECTICUT.

BELT-CLASP.

1,085,633.

Specification of Letters Patent.

Patented Feb. 3, 1914.

Application filed November 9, 1912. Serial No. 730,420.

To all whom it may concern:

Be it known that I, CHARLES E. SACKETT, a citizen of the United States, residing at Danbury, in the county of Fairfield and State of Connecticut, have invented a new and useful Improvement in Belt-Clasps, of which the following is a specification.

This invention relates to a belt clasp, the object being to provide a clasp which permits one end of a belt to be secured to it, and the opposite end after being passed around the waist and through the clasp to be drawn as tight as desired, the strain upon the belt being taken up by the clasp automatically and the belt held fast at any point where such drawing action is stopped, without the use of pins or punctures or defacing the materials.

The clasp has the additional advantage over all pin clasps or buckles that it holds the belt flat, and that the holding strain bears equally upon the entire width of the belt, thus causing the clasp and belt to lie flat against the person. It is equally well adapted to be used as a scarf clasp when loosely draped.

The front member of the clasp can be made in any of the ornamental designs usual to belt buckles or clasps, while the back member of the clasp to which is attached the automatic holding mechanism may be hinged to any of the aforesaid front member designs.

On June 8th, 1912, I filed Serial Application No. 702,633, in the Patent Office of the United States, which has since matured into Patent No. 1,064,013, for a "draw clasp," which patent described a clasp which permitted cords, tapes, ribbons and the like to be drawn through the clasp in both directions, and which automatically held such materials in fixed relation wherever such drawing action was stopped. That invention consisted of two body plates hinged and clasped together, open at opposite ends, and having a swinging central intermediate plate which divided the clasp into two compartments, in each of which an automatic bond and release mechanism was operative to hold and unite two pieces of material passing through the clasp in opposite directions.

In the present invention, the same hinged

and clasped body members are used, but as a belt is only drawn in one direction, the double compartment is unnecessary, and the central intermediate toothed plate is pivoted to either one of the clasp body plates, swings with it, and its teeth bear directly upon the opposite body plate across the passage through which the belt is being drawn.

The invention is fully described and illustrated in the accompanying specification and drawings, in which—

Figure 1, is a front view of a belt clasp, Fig. 2, an end view, Fig. 3, the back member of the clasp, the front being removed, Fig. 4, the same with intermediate plate in position, Fig. 5, a sectional view through line B, of Figs. 1 to 4, Figs. 6, and 7, show alternative spring movements, Fig. 8, a belt clasp with ornamental front member in position on a belt, Fig. 9, the same clasp open for insertion or removal of a belt, the spring movement being that shown in Fig. 7.

In all the figures like numerals relate to like parts.

1, and 2, are the two outer body members of the clasp, hinged together on one side by the hinge pivot 3, and clasped together on the opposite side by the latch, 4. The body members are shaped to provide a suitable space between them, closed on all sides except inlet and outlet spaces 5 and 6, at two of its opposite sides or ends, (see sectional Fig. 5.)

Within the clasp is pivotally secured near one side of the back body plate member an intermediate plate 10. This plate is provided with a series of teeth or projections 12, upon the edge opposite to its pivoted edge. The plate has shoulders 8, turned at right angles to it at top and bottom, perforated to receive the pivot 9. The shoulders are fitted in slots 19, in the back body plate in which member the pivot is retained. The intermediate plate is curved vertically along its pivoted side to provide an extension edge adjusted to contact with the side 18, of the back body plate to prevent undue expansion of the intermediate plate when the clasp is opened. This expansion is caused by a concentric spring 13, shown in Fig. 5, which is interposed between the plate and the back body member, or it may be caused by a

- spiral spring 13 arranged upon the pivot 9 as shown in Figs. 7, and 9. In either case when the clasp is closed upon the intermediate plate it compresses the spring and a suitable pressure is exerted upon the toothed edge of the intermediate plate to bear flexibly against the inside of the front body plate, or upon any ribbon, belt or scarf that may be passing through the clasp.
- 10 The intermediate plate when so compressed is nearly parallel with both body members, and its teeth lie so flat as not to puncture the belt material, but by their slight inclination across the passage between the clasp body members, and a slight additional curvature at point aided by the pressure of the spring successfully resist any return movement of the belt, while freely allowing it to be drawn through the clasp.
- 15 Near the side of the back body member of the clasp, opposite to its pivoted side, a long slot 15, is perforated through it. In this slot is secured one end of the belt. To operate the clasp it only remains to pass the belt around the waist over the face of the intermediate plate in the direction the teeth point, then to snap the clasp shut and draw the belt as tight as desired, and it will hold in any position until the clasp is opened by releasing the catch.

- 25
- 30

Having thus described my invention, what I claim and desire to secure by Letters Patent is:

1. In a belt clasp, the combination of two body plates hinged together at one edge, and having a separable clasp-connection at another edge, said body plates being formed to provide a space therebetween, said space being open at the ends to form a passage between said body plates, an intermediate plate arranged in said passage pivotally connected at one edge to one of said clasp body plates, the opposite edge of said intermediate plate being serrated, and swinging free to contact with the interior surface of the opposite clasp body plate, a spring interposed between said intermediate plate and the clasp body plate to which it is pivoted, said spring causing said serrated edge to bear flexibly against the inner side of said opposed body plate, and to exert compression upon any materials passing between said intermediate plate and said clasp body plate, said serrated edge being so shaped as to allow free passage to a belt ribbon drawn through said clasp in one direction, and to resist any reflex action in a return direction.

2. In a belt clasp, the combination of two body plates hinged together at one edge, and joined by a separable clasp-connection, said body plates being formed to provide a space therebetween open at both ends to provide a passage between them, an inter-

mediate plate arranged in said passage pivoted at one edge to one of said clasp body plates, its opposite edge being serrated, said intermediate plate having a swinging movement at right angles to the hinge movement of said clasp body plates, a spring arranged between said intermediate plate and the clasp body plate to which it is pivoted, said spring exerting an outward thrust upon the free edge of said intermediate plate to open said clasp when said clasp-connection is released, means to limit the outward thrust of said intermediate plate, the closing of said clasp compressing said spring thereby causing it to exert a flexible bearing pressure on the free serrated edge of said intermediate plate, and upon anything against which it contacts.

3. In a belt clasp, the combination of two body plates hinged together at one edge and joined by a separable clasp-connection, said body plates being formed to provide a space therebetween open at both ends to provide a passage between them, an intermediate plate pivoted in said passage to one of said body plates and having a swinging movement at right angles to the movement of said clasp body plates, said intermediate plate being flexibly arranged, and adapted to fold automatically between said clasp body plates when said clasp is closed, and to exert automatically a lateral bearing pressure upon any materials drawn through said clasp in one direction, and to resist their return in an opposite direction.

4. In a belt clasp, the combination of two body plates hinged together and joined by a separable clasp-connection, said body plates being formed to provide a space therebetween an intermediate plate arranged in said space, pivoted at one edge, and having a swinging movement at right angles to the movement of said clasp body plates, an elongated slot made in one of said body plates parallel with the swinging movement of said intermediate plate for the purpose of securing one end of a belt ribbon which has a parallel drawing movement across the face of said intermediate plate.

5. In a belt clasp the combination of two body plates hinged together at one edge, and joined by a separable clasp at the opposite edge, said body plates being formed to provide a space therebetween, said space being open at both ends to form a passage between said body plates parallel with their hinge pivot, and at right angles to their hinge movement, an intermediate plate arranged in said passage pivotally connected to said clasp body plates, said intermediate plate having a swinging movement in line with the hinge movement of said clasp body plates, and an automatic spring-actuated independent swinging movement

across the line of said passage, said intermediate plate having a free serrated edge adapted to release materials drawn through said passage between said clasp body plates 5 in one direction, and to resist the return of said materials.

In testimony whereof, I, CHARLES E.

SACKETT, have signed my name to this specification in the presence of two subscribing witnesses, this 26th day of Sept. 1912.

CHARLES E. SACKETT.
